UNITED STATES PATENT OFFICE.

LUTHER V. RHODES, OF ALTOONA, PENNSYLVANIA.

NEEDLE-THREADER.

No. 879,003

Specification of Letters Patent.

Patented Feb. 11, 1908.

Application filed January 12, 1907. Serial No. 351,991.

To all whom it may concern:

Be it known that I, LUTHER V. RHODES, a citizen of the United States of America, residing at Altoona, in the county of Blair and State of Pennsylvania, have invented new and useful Improvements in Needle-Threaders, of which the following is a specification.

My invention has relation to improvements in needle threaders and it consists in the construction and arrangements of parts as will be hereinafter described and particularly pointed out in the claim.

In the accompanying drawing, Figure 1 is a perspective view of the magnifier and its supporting arm. Fig. 2 is a side elevation of a sewing machine showing my needle threader mounted thereon.

Referring to the drawing for a more particular description of my invention, the numeral 1 designates a magnifying glass mounted upon an arm 2^b, provided with a twisted portion c, and a hinged portion d, provided with a leaf e designed to be pivoted through an opening F, to the frame of a sewing machine as shown in Fig. 2. The twisted portion c of the arm 2^b permits of the glass to be held at the required angle to see the eye of the needle held in stationary position in the needle bar of the sewing machine. I wish it to be understood that the arm is capable of

being thrown upwardly by means of its hinged connection to allow of its having a lateral movement by means of its pivotal portion F to permit of its engagement with a keeper g, which is secured to the frame of the sewing machine. A lug or projection g is provided upon the arm 2^b for moving the magnifier toward and from the needle in order to attain the required focus.

Having thus described the invention, what I claim is:

A needle threader comprising a sewing machine frame, a magnifying glass having a twisted arm with a hinged connection therewith pivoted to said frame, a lug on the arm 45 a keeper on the frame, said arm serving to be thrown upwardly by means of its hinged connection to permit of its having a lateral movement by means of its pivotal connection to engage the keeper, and said lug serving to move the magnifier toward or from a needle so as to obtain the required focus for threading the same, substantially as specified.

In testimony whereof, I affix my signature in presence of two witnesses.

LUTHER V. RHODES.
